UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

MACHINE AND PLANT FOR CASTING AND COOLING TUBULAR STEREO TYPE PRINTING PLATES.

Application filed April 19, 1921. Serial No. 462,733.

To all whom it may concern:

Be it known that I, HENRY A. WISE Wood, a citizen of the United States, residing at New York, in the county of New 5 York and State of New York, have invented a new and useful Machine and Plant for Casting and Cooling Tubular Stereotype Printing Plates, of which the following is a specification.

10 This invention relates to the production of tubular stereotype printing plates, namely, plates which constitute practically a complete circle as distinguished from the ordinary semi-cylindrical plates. These 15 plates substantially cover the entire cylinder of a press and are formed originally in their complete cylindrical condition. They are removed from the mold by turning the core which is provided with a helical 20 groove forming a corresponding helical rib on the inside of the plate.

The principal objects of this invention are to provide an improved arrangement whereby a pair of tubular plate casting 25 machines can be supplied from one source of metal supply and will deliver conveniently to a single cooler which takes care of the product of both machines; to provide this cooler in such form that it will not 30 only receive the plates from two casting machines alternately but will deliver them to a single finishing machine; to provide improved means for operating the core for the purpose of rejecting the casting; to provide 35 for the casting of continuous ribs on the plate extending across the gap which is to be provided, and means for automatically cutting off these ribs across the gap; to provide simple and convenient means for 40 holding the casting box either in its vertical position for receiving or in its horizontal position for delivering; to provide improvements in the mechanism for operating the core and cooling it; and to provide improvements in the cooling mechanism itself.

Further objects and advantages of the invention will appear hereinafter.

Reference is to be had to the accompanying drawings in which—

Fig. 1 is a plan of a casting plant carrying out the above mentioned objects;

Fig. 2 is a plan on a larger scale of one of the casting boxes and associated parts;

Fig. 3 is a side view of the same in horizontal position; 55

Fig. 4 is a side view of part of the box in horizontal position with the supporting shaft in section to illustrate the cam for operating the clutch for starting the 60 core;

Fig. 5 is a side view on an enlarged scale, and partly in central section, of the casting box in upright position ready for pouring;

Fig. 6 is a still further enlarged sectional 65 view of the bottom of the mold cavity;

Fig. 7 is a sectional view of the plate cast therein showing the ribs across the gap;

Fig. 8 is a sectional view of the device for 70 cutting off the ribs;

Fig. 9 is a transverse sectional view of the casting box on the line 9—9 of Fig. 2 showing the cooling chambers;

Fig. 10 is a view of the delivery end 75 of the casting box;

Fig. 11 is a longitudinal central section of the lower end of the casting box showing the water circulating system;

Fig. 12 is a transverse sectional view on 80 the line 12—12 of Fig. 11;

Fig. 13 is a transverse sectional view of the casting box on a small scale showing it open;

Fig. 14 is a sectional elevation of the 85 cooler, and

Fig. 15 is a cross-section of the same on the line 15—15 in Fig. 14.

I have shown the invention in a form in which a single melting furnace or pot 10 90 is provided with a spout 11 adapted to turn to two positions, substantially at right angles to each other with respect to the circular pot or furnace 10. It delivers to two casting boxes located with their axes 95 at 90° apart around the circumference of the furnace or pot. These casting boxes therefore are arranged in such position, as shown in Fig. 1 that their central lines converge to a point of delivery as will appear 100 later.

Each of the casting boxes 15 is mounted on a frame 13 which is provided with two bearings for trunnions 14 projecting from the sides of the box 15. The box is provided with longitudinal pivots 16 and with a cover 17 which is adapted to be opened 105 as shown in Fig. 13 for the insertion of

the matrix M. This cover is secured to the bottom of the box by a pivoted lever 18 engaging a pin 19.

The casting chamber consists of the cavity between the two parts 15 and 17 of the casting box and a core C of full cylindrical form rotatably mounted therein and provided with a continuous helical groove c' on its surface. The usual matrix 10 M and head ring H are provided and also the pouring sheet S at the outer end of the box. The straight edges of the matrix are held in slits along the sides of the margin bar B which extends all the way across 15 the mold cavity and throughout its length.

The box being closed and in condition for casting, it can be turned from the horizontal position shown in Figs. 1, 2 and 3 into the vertical position shown in Fig. 5 and illustrated also in dotted lines in Fig. 1. This 20 is the casting position.

Fixedly mounted with respect to the frame 13 on each side is a cam 23 having two surfaces on which a roller 21 is adapted 25 to rest. This roller is mounted on a pivoted arm 22 and held against the cam by a spring 27. The cam 23 being stationary, it will be understood that upon the rotation of the box from horizontal to vertical position the 30 relation of the cam to the roller 21 will change from that shown in Fig. 4, where the box is horizontal, to that shown in Fig. 5 where it is vertical.

Pivoted to the arm 22 is a link 24 and 35 these parts are duplicated on the two sides of the machine. These links have perforated ends 25 which receive the ends of a pair of studs 26 projecting through slots 28 in the end cap 30 of the mold. These studs 40 26 are bolted to projections on a clutch ring 31 which is slidably mounted on a hub 32 inside the end cap. This hub is rotatably mounted on a cylinder 33 which constitutes 45 the end of the core C in the mold. The clutch ring is provided with a pair of longitudinal pins 35 each extending through slots in a loose gear 36.

The springs 27 normally force the clutch ring 31 and the pins 35 to the left in Fig. 50 11. The ends of these pins bear on the flat surface of a circular plate 38 which is bolted to the end plate 39 of the mold proper and which in turn is bolted to the cap 30. On the end of this cap is a hollow plate 49, the 55 end of which is sealed by a packing. These parts 38, 39, 40 and 30 constitute a single element, therefore, containing a chamber and receiving some of the mechanism above described.

60 The face of the plate 38 is provided with two depressions or notches 41 for receiving the pins 35. Obviously if the gear 36 is rotated when the arms 22 are swung over into the left hand position, that is, when 65 the mold is horizontal, these pins 35 will

spring into the notches 41 and take up the structure 38, 39 40 and 30 and rotate it. Furthermore, the plate 38 is keyed to the cylinder 33 and therefore the core will rotate with it. The mold 15, however, is not 70 a part of the rotary mechanism.

It may be stated at this point that the operating mechanism is driven by a sprocket chain 42 or any other desired device acting on a sprocket wheel 43 which is 75 fixed to a sprocket wheel 44, the two of which are freely rotatable on one of the trunnions 14. From the sprocket wheel 44 a chain 45 drives a sprocket wheel 46 on the end of a shaft 47. On this shaft 47 there is a worm 48 meshing with the worm wheel 36 and driving it constantly. As 80 these parts rotate around the trunnions 14 as a center this rotation can be kept up at all times if desired while the casting is being made, or it can be controlled to start it when desired. In either event the worm wheel 36 rotates idly until the pins 35 engage in the notches 41 and then the core 85 will be rotated.

The helical groove extends around and along the core and a continuous helical rib, therefore, is produced on the casting. The result of this rotation of the core, while the outside of the casting box is held stationary, is to force the core in a rectilinear direction out of the end of the box. Although the margin bar B provides a longitudinal marginal opening throughout the length of the plate P, the helical grooves 95 on the core are continuous and they cause connecting ribs R to be cast on the plate P projecting across the margin gap or opening. The ribs therefore are continuous. As the plate P is moved forward these ribs are 100 cut off by a knife 50 secured to the bracket 51 which is attached to the outside of the box and constitutes a support and bearing for the upper and outer end of the core. 105

It was stated above that the two casting boxes were located in position so that their lines of delivery converge toward each other. The point at which these lines meet is located at the center of a stand 55 on which is rotatably mounted a support 56 having 110 at each end a narrow upward projection 57. These projections support bearings at the top for the studs 58 of a plate cooling support. Through one of these studs passes 115 a pipe 59 for supplying water to the interior of the plate, said pipe being perforated for that purpose. A pair of circular ends 60 are mounted on the studs 58. What 120 may be termed a cooling chamber is formed on these ends and the cast plate P when located in position and supported by them. The two projections 57 are narrow enough to be received in the margin opening or gap, 125 in the plate as indicated in Fig. 15.

This support 56, being swiveled on a ver- 130

tical axis at the point of intersection of the two central lines of the two casting boxes, the whole device can be turned from central full line position shown in Fig. 2 to either 5 one of the dotted line positions. It is held in either of those positions by stops 61, preventing its going further around than the exact position in which it is in alignment with a casting box. This cooling device 10 is therefore in the form of a skeleton saddle for receiving the plate, the plate itself constituting the outer wall of the saddle and receiving the spray from the pipe 59. Inside this saddle there is a central dividing plate 62 for directing the overflow down 15 through the opening in the bottom of the saddle formed by the margin opening in the plate P. This water collects in the bottom of the support 56 and runs down through a central opening 63 into the hollow column 55 and is drained from that through a drain pipe 64.

The cooler can be turned from either of its dotted line positions, in which it is to receive the plate, to the full line position shown in Fig. 1 for delivering the plate directly and in a straight line to the finishing machine 70. The finishing machine may be of any type and the details of it 30 are not shown herein.

In the casting of the plate, starting with the box in horizontal position, the hinged cover 17 of the casting box is thrown open as shown in Fig. 13 and the matrix placed 35 in position against the head ring H. It is bent circumferentially and its straight edges engage the margin bar B which extends throughout the length of the casting chamber. The pouring sheet S is then put 40 in place overlapping the circular end of the matrix. The hinged cover 17 is closed and locked in position by the lever 18 and then the box is swung up into vertical position. Metal is then poured into the box 45 from the furnace through the spout. Cooling fluid is immediately introduced into the core or box, or both, through flexible connections at the end of the cap.

Now the box, having the cast plate therein, is swung down into horizontal position and cooling fluid is introduced through flexible connections 75 and sprayed on the inside of the core as desired. It is drained off through the opening in the end of the 55 core to the chamber in the end cap and out through the drain pipe 76 as usual. Power is turned on in any desired way so that the chains 42 and 45 will be started. This rotates the wheel 36. When the box has 60 reached horizontal position the rollers 21 on the two sides fall into recesses on the cam 23. The springs 27 swing the arms 22 over to the left and bring with them the clutch ring 31 which holds the pins 35 yielding 65 against the surface of the plate 38.

As soon as the pins 35 come into registration with the notches 41 the springs 27 force these pins into the notches and thereafter the cap end of the mold and core C are rotated positively by the chains. 70

On account of the helical grooves in the core and the fact that the plate is held firmly by the margin bar B, the rotation of the core will start the plate out of the box longitudinally with the matrix thereon. 75 During this motion of the plate forward the ribs are cut through the margin by the knife 50 as stated.

The cooling stand, meantime, has been swung around against one of its stops so 80 that it is in alignment with the casting box and the plate is discharged directly from the casting box into the cooler and, with the attendant's help, finally reaches the position thereon shown in Fig. 14. The 85 water is turned on through the pipe 59 and the cooling of the plate completed while a casting is being produced in the other casting box. When the plate is cooled, the cooler is turned to the full line position and 90 the plate moved out of it by hand into the finishing machine 70.

This provides an arrangement by which two casting boxes can be kept going constantly, one of them delivering a cast plate 95 while the other is made ready to receive the molten metal. It is well known that one cooling device and finishing machine can be operated to take care of the product of two casting machines of this type. It involves no hand labor other than that which would be required for operating a single cooling mechanism and eventually doubles the product of a unit of labor. The cost of machinery is reduced because only one 100 cooler and one finishing machine is required for a double product. No claim is made herein to the casting box by itself. The right is reserved to present claims on that in a divisional application. 110

Although I have described and illustrated only a single form of the invention I am aware of the fact that modifications can be made therein by any person skilled in the art without departing from the scope of the 115 invention as expressed in the claims. Therefore, I do not wish to be limited to all the details of construction or the relative arrangement of parts therein shown and described but what I do claim is:— 120

1. In a stereotype plate casting plant, the combination with a source of supply of molten metal, a cooling stand, and a finishing machine all arranged substantially in alignment, of a pair of casting machines located with their axes at an angle to each other and adapted to receive metal from different sides of said source of metal supply, said cooling stand being arranged to receive a cast plate directly from either of 125 130

the casting device and deliver it to the finishing machine.

2. In a stereotype plate casting plant, the combination of a source of supply of molten metal, a cooling stand, and a finishing machine arranged in alignment, with a pair of casting machines located with their axes substantially at right angles to each other and adapted to receive metal from different sides of said source of metal supply, said cooling stand being movable to three positions, in two of which it is located and adapted to receive a cast plate directly from one of the casting devices and in the third position it is located to deliver to the finishing machine in line therewith.

3. In a plant for making stereotype printing plates, the combination of two casting machines, a molten metal supply device, and a cooling stand, said cooling stand being adapted to turn to two positions in each of which it is in alignment with one of the casting devices.

4. In a plant for making stereotype printing plates, the combination of two casting machines, a molten metal supply device, and a cooling stand arranged substantially in the form of a square, said cooling stand being adapted to turn to two positions substantially at right angles to each other in each of which it is in alignment with one of the casting devices.

5. In a stereotype plate casting device, the combination of two casting machines arranged at an angle to each other in position to deliver at substantially the same point, and a pivotal cooling stand located at said point and adapted to be turned to two positions in each of which it is in alignment with one of the casting devices.

6. In a stereotype plate casting device, the combination of two casting machines arranged at an angle to each other in position to deliver at substantially the same point, each of said casting machines comprising a cylindrical mold mounted to swing on a horizontal axis from a vertical position for receiving molten metal to a horizontal position for delivering toward said point, and a pivotal cooling stand located at said

point and adapted to be turned to two positions in each of which it is in alignment with one of the casting devices when in horizontal position.

7. In a casting device, the combination with a tubular casting box, of a cylindrical core rotatably mounted therein and having a continuous helical groove on its casting surface, a matrix bar extending longitudinally along the core from the surface of said core to the inner surface of the box, whereby a continuous helical rib is cast on the plate inside and across the space occupied by the matrix bar, continuations of said rib being cast spaced from each other and with their inner surfaces against the matrix bar, means for turning said core to eject the plate in a rectilinear direction, and a stationary cutter on the box for engaging and cutting off the ribs across said space as the plate is withdrawn.

8. In a casting device, the combination with a casting box adapted to cast a cylindrical plate with a longitudinal gap and deliver it in a horizontal position, of a cooling stand having narrow arms projecting upwardly from its opposite ends for receiving the gap in the plate, said stand being adapted to be turned into longitudinal alignment with the casting box and having means for supporting the cast plate to be cooled and provided with a water pipe inside having openings for spraying water on the interior of the plate while it is held by said means.

9. In a cooling device for a cast cylindrical plate, the combination of a pair of circular end plates on which the plate to be cooled can be mounted, a pipe extending longitudinally between them having perforations to permit of spraying water on the inside of the plate, said cooling device having a chamber for receiving the water therefrom and provided with an outlet drain and having a pivotal support by which it can turn on a vertical axis concentric with said drain.

In testimony whereof I have hereunto affixed my signature,

HENRY A. WISE WOOD.
